ORDNANCE

Gerard E. Schultz, Buffalo, N. Y., assignor to Bell Aircraft Corporation, Buffalo, N. Y.

Application July 23, 1943, Serial No. 495,885

4 Claims. (Cl. 89—34)

This invention relates to ordnance, and more particularly to ammunition magazine means for feeding rapid fire cannon or machine guns or the like. The magazine is of the type which is adapted to store and feed relatively heavy caliber ammunition rounds, as in connection with rapid fire cannon mounted upon combat aircraft, or the like; and a particular feature of the magazine is that it is suited to be mounted with improved results within an airplane fuselage or nacelle for feeding ammunition to rapid fire type guns mounted upon the same structure.

It is a primary object of the present invention to provide an improved ammunition magazine of the character referred to and which comprises essentially a continuous track upon which ammunition rounds are carried to be laterally slidable in side-by-side relation by means of a feed control belt training adjacent the track for feeding the ammunition rounds successively into the associated gun. More specifically, it is an object of the present invention to provide improvements in track-type magazines of the character aforesaid, whereby dimensional variances with respect to ammunition feed control belts successively mounted upon the magazines may be quickly and effectively compensated for by manual adjustment of the track structure. Another more specific object of the present invention is to provide in a magazine of the character aforesaid an improved track section collapsing and dimensional adjustment means, whereby the magazine track will be adapted to be serviced with fresh ammunition in improved manner and to be adjusted in connection with each servicing thereof in improved manner so as to maintain the ammunition load therein in ideal gun feeding condition. Other objects and advantages of the invention will appear from the specification hereinafter.

In the drawings:

Fig. 1 is an end elevation of a magazine of the invention, shown as being mounted within an airplane fuselage and in conjunction with a rapid fire cannon;

Fig. 2 is a section, on an enlarged scale, taken along line II—II of Fig. 1;

Fig. 3 is a side elevation, on an enlarged scale, of the magazine of Fig. 1;

Fig. 4 is a fragmentary view, on an enlarged scale, of details of the track section collapsing and dimensional adjusting mechanism of the invention as applied to the magazine of Fig. 1; and

Fig. 5 is a bottom plan view of a pair of ammunition feed control belt sections arranged in an articulated relation.

The drawings illustrate the invention as being embodied in an ammunition magazine mounted within an airplane fuselage which is generally indicated at 10, and in operative relation with respect to a rapid fire gun or cannon indicated

generally at 12. The cannon 12 is illustrated as being disposed substantially parallel to the longitudinal axis of the airplane fuselage 10, and approximately centrally thereof; the gun ammunition feedway portion thereof being illustrated at 14 to comprise a casing open at opposite sides thereof for registry with corresponding end portions of the ammunition magazine and with the continuous rounds feeding belt device thereof.

Thus, the gun and magazine unit is arranged so that rounds of ammunition will be moved laterally while in side-by-side relation into the ammunition feedway casing 14 of the gun, to be then acted upon successively by the ammunition feed pawl mechanism of the gun so as to be stripped from the magazine feed control belt and pulled downwardly into the charging mechanism of the gun. Intermediately of the gun charging operations the ammunition carrying belt of the magazine will be rotated by the gun feed pawl mechanism so as to pull the next succeeding ammunition round into the feedway casing 14 of the gun.

To provide the operation referred to hereinabove, the ammunition magazine comprises a generally C-shaped track-like structure (Fig. 1) including a pair of U-shaped sections 15—15 each of which comprises a frame including a pair of opposed end plates 16—16 which are maintained in spaced parallel arrangement by means of a plurality of cross bars 18 connected thereto by screws or other suitable connectors at 19. The end plates 16—16 are spaced so as to accommodate in lengthwise attitude therebetween the rounds of ammunition as indicated at 20 for feeding the gun 12. Each end plate 16—16 is formed with a horizontally disposed flange 21 adapted to provide an annular ledge upon which will rest the corresponding end portions of the ammunition rounds 20.

The two frame sections 15—15 interconnect at the upper reach of the magazine so as to dispose their end plate and ledge portions in smooth continuation of one another. The connection between the frame sections is made to be detachable, as by over-lapping lug portions at 22 and spring pressed pins 23 carrying integral fingers 24 which are adapted to be manually manipulated for retraction of the pins to disconnect cooperating lug portions of the frames. At the lower reach of the magazine structure the frame sections 15—15 terminate in opposed end portions which are so spaced to accommodate therebetween the ammunition feedway casing portion 14 of the gun; and suitable detachable connection latch devices as indicated at 26 are provided to be adjusted by manual manipulation of spring-pressed control pins as indicated at 28, and by cam-type pin and finger connectors as indicated at 30. It will be understood that the connectors may be of the type shown at the upper reach of the magazine, or of

the type shown at 26-28, whichever may be preferred.

Thus, it will be appreciated that the magazine comprises an annular trackway adapted to fit upon the ammunition feedway casing of the associated gun to provide a smoothly curving closed circuit ammunition trackway structure. The end plate devices of the trackway elements have both horizontally extending ledges to support the weight of the ammunition and vertical end plate portions to maintain the ammunition rounds in longitudinally guided relation, whereby a plurality of ammunition rounds may be mounted upon the ammunition trackway to be disposed in side-by-side relation and to be freely slideable in sidewise direction upon the circuitous trackway for feeding of the ammunition rounds successively into the ammunition feedway casing 14 of the associated gun.

To maintain the ammunition rounds in proper relative positions and to cause the rounds to be fed positively to the cannon, a feed control belt is provided to comprise a plurality of linked plates each of which is adapted to detachably connect to a corresponding ammunition round and to be linked together to comprise an endless belt lying adjacent the inside profile of the ammunition load of the magazine and to register with the ammunition feed pawl mechanism of the gun and to be driven thereby to intermittently rotate the entire ammunition load of the magazine in the direction of ammunition feeding to the extent required to feed one round to the gun. As illustrated in Fig. 5, the ammunition feed control belt is provided to comprise a series of belt plates 35 which may be stamped from sheet metal or the like or otherwise formed to comprise generally square shaped metal plates having paired lugs 36-36 and 37-37 extending from opposite ends thereof and at laterally offset positions so as to be adapted to register in side-by-side relation with opposite lugs of the next adjacent of said plates when arranged in continuous belt-like formations. Pins 38 are fixed to extend from one pair of said lugs so as to be adapted to be slipfitted into hinge connection relation with the lugs of the next adjacent belt plate; and the connection lugs and pins are so dimensioned and relatively arranged that the feed control belt may be readily assembled and disassembled by simple sidewise movements of one belt plate 35, relative to a next adjacent belt plate 35.

Each belt plate 35 is also provided with a U-shaped spring clamp device having opposed spring finger portions 40-40 extending normally to the plane of the plate and so dimensioned and arranged as to be adapted to reach outwardly into resilient gripping relation upon opposite sides of the ammunition round to be mounted upon the plate (Fig. 3) at the central body portion thereof. Thus, the clamp fingers 40 are adapted to receive in cradled relation therein the mid-section of a single ammunition round when pressed thereinto against the resiliency of the clamps, and each belt plate 35 thus mounts an individual ammunition round and acts to maintain adjacent rounds in properly spaced relation in accord with the feeding requirements of the mechanism of the associated gun. Cradle plates 44-44 may also be carried by each of the belt plates 35 at positions spaced longitudinally of the round to provide accurately positioned cradling of each ammunition round upon the belt plate.

To position the feed control belt relative to the magazine structure and the ammunition load,

and to support the feed control belt for free sliding movement relative to the magazine fixed structure, a belt slide track is fixed to the magazine structure at a position intermediately of the end plates 16-16 of the magazine frame, as indicated generally at 45. The slide trackway 45 comprises generally a pair of spaced end plates 48-48 having vertically disposed inner surfaces spaced apart so as to accommodate therebetween the control belt plates 35-35 for free sliding mounting of the control belt within the space between the end plates 48-48. The plates 48-48 are carried by the cross bars 18 by being permanently mounted thereon. A pair of slide rails 50-50 are also carried by the cross bars 18 to be disposed intermediately of the end plates 48-48 and to register at their outer surface portions with the prescribed contour of travel of the feed control belt. Thus, the belt is arranged to be radially supported upon the magazine structure by means of the slide rails 50-50 so as to be freely slideable therearound while being guided against disalignment relative to the magazine in directions longitudinally of the ammunition rounds by means of the end plates 48-48. As shown in Fig. 3, the end plates 48-48 are so shaped at their outer edge portions to extend outwardly and beyond the profile level of the feed control belt plates when the belt is assembled and mounted in operative position, and it is arranged that the control belt is perimetrical dimensioned so as to hug the slide rails 50-50 snugly, thus preventing the belt plates 35 from jumping over the end rails 48-48 and out of proper operational alignment.

To enable the feed control belt to be assembled and disassembled relative to the magazine trackway, the feed belt slideway is arranged to include at a curved profile portion thereof a hinged track section which is adapted to be retracted, when desired, so as to shorten the total dimension perimetrical of the belt slideway. Thus, when it is desired to install the feed control belt in operative relation upon the magazine, the retractable belt slideway section is first released to shorten the distance around the slideway. A feed control belt having the prescribed number of belt plates 35 will then be wrapped about the magazine so as to be generally residing within the belt slideway. The two loose ends of the belt will then be brought into connecting registry. As explained hereinabove, interconnection of the two end belt plates may be then effected by first disposing the plates in approximate registry but with their coacting lug and pin portions to be in laterally offset relation. Simple sidewise relative movement of the two adjacent belt plates will thereupon cause the connecting pins to slip into linking position, and the entire belt assembly will then be in operative alignment.

To effect a connection, as described hereinabove, and to enable adjacent of the belt plates to be brought into connecting registry while being offset laterally from one another, it is necessary that the belt plates be so manipulated while being disposed beyond the reach of the end plate portions 48-48 of the slide-track. Retraction of the slideway portion referred to hereinabove enables the interconnecting belt plate portions to be so disposed beyond the reach of the end plate portions 48-48 during the belt connection operation. Then, upon completion of the belt connection, the retractable slideway section will be adjusted to its extended position so as to lie in smooth continuation of the profile of the main slideway

portions and to extend the perimetral dimension of the slideway to the prescribed operative length thereof so as to cause the connected feed control belt to be pulled into firmly guided relation between the end plates 48-48 and to hug the slide rails 50-50 snugly.

To disassemble the feed control belt from the magazine structure the above described operation is simply reversed. That is, the retractable slideway section is first released so as to hinge inwardly to reduce the perimetral dimension required to be occupied by the feed belt. The feed belt is thereby relaxed so as to be adapted to be withdrawn at any convenient point about the slideway away from the reach of the end plates 48-48, whereupon any two adjacent belt plates 35 may be relatively displaced by manual manipulation in opposite lateral directions so as to disconnect the corresponding pin and lug devices. Thereupon the feed control belt is disconnected and is free to be taken from the track.

To accommodate the above described procedures the belt track rails 50-50 may be terminated as indicated at 52 (Figs. 2, 3, 4), and the space between the terminal positions 52-52 is arranged to be substantially occupied by a pair of correspondingly shaped arcuate rail sections 54-54 disposed in spaced parallel relation, as viewed in Figs. 2-3, so as to register in directional alignment with the track sections 50-50, while being arcuately shaped in side elevation as shown in Fig. 4 to complement generally the curved profile form of the track section. The rail sections 54-54 are interconnected by means of upper and lower sleeves 56-57 to provide a rigid frame-like structure. The lower sleeve 57 is rotatably mounted upon the corresponding cross bar 18 so as to cause the rail sections 54-54 to be freely pivotable as a unit about their mounting upon the lower cross bar 18 in directions radially of the magazine. The rail sections 54-54 and the pivotal mounting thereof at 57 are so arranged as to anchor the lower ends of the rails 54-54 in approximate registry with adjacent terminal end portions of the rail sections 50-50, in any position of swinging adjustment of the rail sections 54-54.

To control the swinging movement of the retractable rail section, the upper sleeve 56 is arranged to carry in rotatable relation thereon a collar 60 upon which is formed a boss 62. A lever 64 is mounted at one end portion thereof within the boss 62 in such manner as to resist relative movement between the boss and the lever in directions longitudinally of the lever, while the lever is free to rotate relative to the boss. Immediately of its ends the lever 64 is screwthreaded through a block 66, and the block 66 is formed with a pair of oppositely extending nubs 68-68. The nubs 68-68 are arranged to extend in free sliding relationship into arcuately slotted portions 69-69 of a pair of guide plates 70-70 which are disposed in upright parallel spaced relation at opposite sides of the retractable track section and at corresponding positions between the end plates 48-48 and the corresponding rail sections 54-54. The plates 70-70 are permanently stationed upon the magazine structure, as by being threaded at suitable apertured end portions thereof upon the cross bars 18-18 which lie adjacent the retractable track section. Thus, as illustrated in Fig. 4, the plates 70-70 extend somewhat diagonally and vertically to subtend the arc of the retractable track section. A spring finger type detachable clamp device as illustrated

at 72 is mounted upon each plate member 70, and the fingers thereof are so arranged as to resiliently grip upon the nub 68 extending through the slotted portion 69 of the plate whenever the screw block 66 is swung upwardly so that the nubs 68-68 are disposed at the end portions of the slots 69-69.

The lever 64 is fitted at its outer end with a knob or wing nut 75 or the like which is keyed to the lever whereby manual turning of the knob will rotate the lever upon the boss 62 and thereby cause the block 66 to move in a direction longitudinally of the lever, according to the direction of rotation of the knob. Thus, it will be understood that the lever 64 may be manually adjusted by rotation of the knob in such manner as to regulate the distance between the upper end of the retractable track section and the nubs 68-68 so that when the knob end of the lever is pulled upwardly to dispose the nubs in gripped relation within the clamps 72-72 the upper end of the swinging track section will be thereby extended and disposed in directional registry with the fixed track sections 50-50 while tightening the ammunition feed belt upon the rail sections 50-54. Thus, it will be understood that subsequent to installation of every new feed control belt upon the magazine trackway the knob 75 may be manually drawn into the uppermost position thereof as shown in Fig. 4 and thereupon rotated relative to the block 66 so as to force the swinging end portion of the retractable track section outwardly against the ammunition feed control belt to provide any desired degree of tightening thereof. The spring clamps 72-72 will thereupon maintain the screw 64 normally in track holding position.

To permit the retractable trackway section to be quickly collapsed, as for rapid disassembly of a damaged ammunition feed belt from the magazine in accord with the procedure outlined hereinabove, the slotted portions 69-69 of the plates 70-70 are formed to extend downwardly from the normal position of the nubs 68-68 and in arcuate direction, so as to enable the knob carrying end portion of the lever 64 to be pulled manually downwardly from the solid line position thereof shown in Fig. 4, to break the engagement between the nubs 68 and the clamps 72. Thus, the nubs 68 are then free to slide downwardly through the slots so as to permit the lever and collar unit 64-60 to rotate while the swinging end portion of the trackway pivots inwardly or in clockwise direction as viewed in Fig. 4 toward the broken line position thereof. Thus, it will be understood that due to this collapsing movement of the retractable track section the perimetral dimension of the feed belt trackway is thereby quickly reduced, and the belt may thereupon be lifted out of guided relation between the end plates 48-48 of the trackway for disconnection of the belt by relative sidewise motions of any two adjacent belt plates, as explained hereinabove.

To install a new belt upon the trackway, the belt is first wrapped about the trackway while the retractable track section is in the collapsed position referred to; the loose ends of the belt are then interconnected as explained hereinabove and laid into the trackway; whereupon the knob 75 is manually moved upwardly to the solid line position thereof shown in Fig. 4 for locking the retractable track section in its extended position. At any time a fine adjustment of the perimetral dimension of the trackway may be effected by

manual rotation of the knob 75, so as to adjust the lever relative to the block 66 to provide the preferred degree of tension upon the feed control belt for operational purposes. As shown in Figs. 2-4, series of rollers 89 may be provided to extend between the paired rail sections 50-50 and 54-54 for rolling support of the feed control belt to ease the movement thereof over the trackway rails in the region of the collapsible section, irrespective of the adjusted position of the retractable rail section.

I claim:

1. An ammunition feed magazine for use in conjunction with a gun, said magazine comprising a frame having a circular ammunition supporting and guiding trackway thereon for mounting a plurality of ammunition rounds in side-by-side relation for sliding movement of said rounds upon said trackway for feeding said gun, a slideway carried by said frame to extend parallel to said trackway and in substantial conformity with the circular profile form thereof, an ammunition feed control belt device encompassing and slidably disposed within said slideway to be guided thereby and having spring finger devices extending therefrom to separately engage said ammunition rounds, said frame having a cam track thereon, said slideway having a curved profile portion thereof structurally separate from other portions thereof and pivotable relative to said other portions for regulating the perimetral dimension around said slideway, manual control means coupled to said pivotal section and extending therefrom into slide bearing connection with said cam track of said frame, said control means and said pivotal section and said cam track being so constructed and arranged whereby said control means may be manually manipulated to slide upon said cam track to cause said pivotal section to rock relative to said other portions, and adjustment means carried by said control means and arranged to be manually manipulated to adjust said control means relative to said cam track to regulate the degree of tensioning of said belt as may be desired in conjunction with rocking of said pivotal slideway section.

2. An ammunition feed magazine for use in conjunction with a gun, said magazine comprising a frame having a circular ammunition track-way thereon for mounting a plurality of ammunition rounds for movement of said rounds upon said trackway for feeding said gun, a slideway carried by said frame to extend parallel to said trackway and in substantial conformity with the circular profile form thereof, an ammunition feed control belt encompassing and slidably disposed within said slideway to be guided thereby and having devices extending therefrom to separately engage said ammunition rounds, said slideway having a portion thereof pivotal relative to said frame for regulating the perimetral dimension around said slideway, said frame having a cam track thereon, manual control means coupled to said pivotal section and extending therefrom into bearing connection with said cam track of said frame, said control means and said pivotal section and said cam track being so constructed and arranged whereby said control means may be manually manipulated to slide upon said cam track to cause said pivotal section to rock relative to said frame, and adjustment means carried by said control means and arranged to be manually manipulated to adjust said control means

relative to said cam track to regulate the degree of tensioning of said belt as may be desired in conjunction with rocking of said pivotal slideway section.

- 5   3. An ammunition feed magazine for use in conjunction with a gun, said magazine comprising a frame having a circular ammunition track-way thereon for mounting a plurality of ammunition rounds for movement of said rounds upon
10   said trackway for feeding said gun, a slideway carried by said frame to extend parallel to said trackway and in substantial conformity with the circular profile form thereof, an ammunition feed control belt device comprising a plurality of belt
15   plates laterally interlocked and slidably disposed within said slideway to be guided thereby and having devices extending therefrom to separately engage said ammunition rounds, said slideway having upstanding end wall portions adapted to
20   maintain said belt plates in self-aligned laterally interlocked form when disposed within said slideway, said slideway having a portion thereof pivotable relative to said frame for regulating the perimetral dimension around said slideway, said
25   frame having a cam track thereon manual control means coupled to said pivotable section and extending therefrom into bearing connection with said cam track of said frame, said control means and said pivotal section and said cam track
30   being so constructed and arranged whereby said control means may be manually manipulated to slide upon said cam track to cause said pivotal section to rock relative to said frame, and adjustment means carried by said control means
35   and arranged to be manually manipulated to adjust said control means relative to said cam track means to regulate the degree of tensioning of said belt as may be desired in conjunction with rocking of said pivotal slideway section.
40   4. An ammunition feed magazine for use in conjunction with a gun, said magazine comprising a frame having a circular ammunition track-way thereon for mounting a plurality of ammunition rounds for movement of said rounds upon
45   said trackway for feeding said gun, a slideway carried by said frame to extend parallel to said trackway and in substantial conformity with the circular profile form thereof, an ammunition feed control belt device encompassing and slidably
50   disposed within said slideway to be guided thereby and having devices extending therefrom to separately engage said ammunition rounds, said slideway having a portion thereof pivotable relative to said frame for regulating the perimetral dimension around said slideway, a cam track upon said frame manual control means coupled to said pivotable section and extending therefrom into bearing connection with said cam track, said control means and said pivotal section and
55   said cam track being so constructed and arranged whereby said control means may be manually manipulated to slide upon said cam track to cause said pivotal section to rock relative to said frame, adjustment means carried by said control
60   means and arranged to be manually manipulated to adjust said control means relative to said cam track means to regulate the degree of tensioning of said belt as may be desired in conjunction with rocking of said pivotal slideway section, and
65   spring latch means carried by said frame and adapted to engage said control means when in cammed belt tensioning position for releasably holding said control means in said position.

means in said position.
